US0D1114096S

(12) United States Design Patent (10) Patent No.: US D1,114,096 S
(45) Date of Patent: * Feb. 17, 2026

(54) DUMBBELL

(71) Applicant: Honghua Hu, Yongkang (CN)

(72) Inventor: Honghua Hu, Yongkang (CN)

() Term: 15 Years

(21) Appl. No.: 29/889,410

(22) Filed: Apr. 12, 2023

(30) Foreign Application Priority Data

Apr. 7, 2023 (CN) 202330185454.0

(51) LOC (15) Cl. 21-02

(52) U.S. Cl.

USPC D21/681

(58) Field of Classification Search

USPC D21/662, 679, 684, 692-694, 685, 686, D21/667, 681-682; D24/215, 143, 141, D24/135; D6/552

CPC A63B 21/00043; A63B 21/0552; A63B 21/0555; A63B 21/4047; A63B 23/20; A63B 2220/51; A63B 21/023; A63B 2220/12; A63B 21/062; A63B 2220/13; A63B 69/3632; A63B 21/075; A63B 21/063; A63B 21/0628; A63B 21/0724; A61B 5/227; A61B 2017/00805; A61B 5/4337; A61H 19/40; A61H 2201/1628

(57) CLAIM

The ornamental design for a dumbbell as shown and described.

DESCRIPTION

FIG. 1 is a front, right and top perspective view of a dumbbell showing my new design;

FIG. 2 is a rear, left and bottom perspective view thereof;

FIG. 3 is a right view thereof;

FIG. 4 is a left view thereof;

FIG. 5 is a front view thereof;

FIG. 6 is a rear view thereof;

FIG. 7 is a top view thereof;

FIG. 8 is a bottom view thereof;

FIG. 9 is an enlarged view of a portion labeled as 9 on FIG. 1;

FIG. 10 is an enlarged view of a portion labeled as 10 on FIG. 2;

FIG. 11 is an enlarged view of a portion labeled as 11 on FIG. 2; and,

FIG. 12 is an enlarged view of a portion labeled as 12 on FIG. 3.

The long dash-short dash broken lines depict enlargement boundaries that form no part of the claim.

1 Claim, 12 Drawing Sheets
